AUTOMATON MERCHANTISING DEVICE

Frank L. Dale, Hartsville, Ind.

Application June 20, 1936, Serial No. 86,380

3 Claims. (Cl. 46—118)

This invention relates to an improved automaton merchandising device.

I contemplate in a generic sense the provision of a robot-like figure which is operated, preferably, by remote control to simulate certain human characteristics, such for example as, movement of the head, smoking, saluting and speaking.

More specifically the invention comprises the figure of a human within the body of which is compactly arranged the mechanism for oscillating the head and simultaneously exhaling smoke from a lighted cigarette through the nostrils, raising one arm from the body to the head, as in saluting, and speaking through a loudspeaker, all of said mechanism being operable electrically at any desired point removed from the automaton.

To the accomplishment of the recited objects and others co-ordinate therewith, the preferred embodiment of my invention resides in the construction and arrangement of parts hereinafter described, illustrated in the accompanying drawings and embodied within the scope of the appended claims.

In said drawings, Fig. 1 is a front elevation of the complete figure.

Fig. 2 is a vertical sectional view taken along lines 2—2 of Fig. 1.

Fig. 3 is a transverse sectional view taken along lines 3—3 of Fig. 2.

Fig. 4 is a detail vertical section of a portion of the head, and

Fig. 5 is a schematic view of the electrical wiring system employed.

Similar reference characters indicate corresponding parts throughout.

Broadly, the figure comprises a body 5, head 6, arms 7 and 8, legs 9 and 10, all constructed from cylindrical elements, as cans or drums.

The body 5 serves as a housing for the major portion of the operating mechanism, and is formed of a relatively large cylinder or drum having a vertical side wall 11, top plate 12 and bottom plate 13.

Head 6 is carried by neck 14 which latter rests upon top 12 of body 5, and both the head and neck are designed to oscillate with respect to the body, as will now be explained. Extending through top 12 of the body and the junction of the head and neck is a tubular member 15, open at both ends, and at its lower end having rigidly fixed thereto and extending laterally therefrom an arm 16, slotted at 17, said arm cooperating with link 18 carried by a small electric motor 19 of the windshield wiper type.

Link 18 has a depending lug 20 which works in slot 17 of arm 16. Upon energizing motor 19 it is apparent through the connections just described, that the tubular member 15 and the head and neck which are fixed thereto will oscillate.

Upon particular reference to Figs. 1 and 4 of the drawings, it will be seen that a mouthpiece 21 is positioned in the mouth 22 and is adapted to receive a cigarette or the like 23. Nose 24 has an orifice 25 at its base, and towards its top and extending through head 6, is a small nipple 26. The inner terminals of mouthpiece 21 and nipple 26 connect with couplings 28 and 29 respectively, said couplings being joined by the T 30 disposed at the upper end of pipe 31 which extends downwardly through the tubular member 15. Each coupling 28 and 29 is equipped with a ball valve 32 and 33. Within housing 11 is a depending bracket 34 which supports a pair of reducing gears 35, crank-shaft 36 and pulley 37. The outer end of crank-shaft 36 is pivotally connected to piston 38 of pump cylinder 39, suitably supported by bracket 40 while a belt 41 is trained over pulley 37 and is operated by an electric motor 42.

A flexible tubing 43, in length ample to resist any undue tensile distortion as the head is oscillated, serves to connect the bottom of pipe 31 and the corresponding end of cylinder 39.

In the reference to Figs. 2 and 3 of the drawings, with respect to the mechanism for elevating the arm, it is noted that shaft 44 extends transversely through body 5 and is rigidly fixed to arm 7 and the figure as at 45—arm 8 remaining stationary. This shaft carries a flanged pulley 46, and below said shaft are a pair of worm gears 47 and 48, the former having mounted thereon a disc 49 and the latter having a pulley 50. A flexible wire or cord 51 connects pulley 46 and disc 49, and belt 52 is connected to motor 53.

In the front of wall 11 of body 5 there is provided a circular opening 54. In juxtaposition to this opening is disposed a loudspeaker 55. Towards the base of body 5 the various conductors noted generally by the reference numeral 56 enter through the small opening 57—being suitably connected to the motors et cetera.

In the schematic view shown in Fig. 5, 58 is the sound-amplifying unit, 59 is a microphone, 60 is a phonographic record turn-table and 61 is a center control outfit. In this showing all circuits can be easily traced from any suitable source of current supply as A and B.

In practical operation the automaton figure is positioned at any suitable location and the con-

trol with its accessories is hooked up at a distant point. By way of example, the figure may be set up in front of a conventional type of gasoline station and the control positioned within the building which usually comprises a part of such stations. Upon closing cut-out switch 62, motor 19 is energized resulting in an oscillating movement of head 6 and neck 14. When cut-out switch 63 is closed, motor 42 becomes energized and through the connection hereinbefore described, piston 38, through suction means, unseats ball valve 32 drawing in smoke from lighted cigarette 23, and upon its down stroke the said piston unseats valve 33 and forces the smoke through flexible tube 43, pipe 31, T 30, and nipple 26 out through orifice 25, thereby simulating the act of smoking.

When motor 53 is energized through closing cut-out switch 64, arm 7 of the automaton is raised as shown in Fig. 1 of the drawings, in imitation of a salute. This result follows through connections 44, 45, 46, worm gears 47, flexible wire 51 and the other associated appurtenances. The salute arm 7 is caused to resume a normal position similar to that of stationary arm 8, by reason of its own weight. The salute may be accentuated if head-oscillating means is actuated simultaneously, for then the movement of the arm and head is synchronized, i. e. as the movable arm 7 starts to move from its normally lowered position motor 19 is energized which causes head 6 to oscillate in profile, and by the time arm 7 is raised to the limit of its swing, head 6 will have returned to create a mechanical simulation of a salute, as illustrated in Fig. 1 of the drawings.

Through the microphone 59 an attendant may greet a customer as he drives up to the station, or the attendant directed in the service of cars by one who may be in charge of the station. The microphone may be employed in various other ways which may suggest themselves to the owner or the operator of the station.

If preferred, on certain occasions a phonographic record can be placed on turn-table 60 and the sound emitted therefrom reproduced through loudspeaker 55. Such record may embody a song, music, sales talk or the like. In this connection the amplifying unit 58 is provided with the usual input and output circuits. Microphone 59 and phonographic producer are each shown connected to the input circuit through the leads 65 and 66 respectively. The output circuit, which may be affected by either microphone 59 or phonographic reproducer 60, is connected by leads 67 to the loudspeaker 55.

The various movements of the automaton and the transmission of sound through the loudspeaker are controllable either selectively or simultaneously. For instance, should the occasion require, only the head and arm of the figure can be caused to operate in the simulation of a salute, or either the head or the arm can be controlled independently of each other. If desired, the head can be oscillated in the absence of a smoking imitation. Various combinations can be worked out to suit the dictates of the particular occasion.

It should be understood that in its broader aspects the invention comprises not only the various means described but similar means for performing the recited functions. It is desired to reserve the right to make such changes or modifications as may come fairly within the scope of the appended claims.

I claim:—

1. An automaton merchandising device including a body, a head oscillatable in a horizontal plane, a pair of arms one of which is pivoted at the shoulder of the body and movable from a point adjacent the lower extremity of the body to a position of salute and motor-actuated means associated with the body whereby upon a single movement of said arm from one position to the other, the head is timed to oscillate from front to profile and profile to front.

2. An automaton merchandising device including a body, a head oscillatable in a horizontal plane, a pair of arms one of which is pivoted at the shoulder of the body and movable from a point adjacent the lower extremity of the body to a position of salute and means operable within the body whereby upon movement of said arm from its lowermost point to salute, the head will concurrently oscillate in profile and return to a front view.

3. An automaton merchandising device including a body, a head oscillatable in a horizontal plane, a pair of arms, one of said arms being movable from a point adjacent the lower extremity of the body to a position of salute, one of said arms being immovable, a mouth-piece carried by the head, means operable within the body whereby upon a single movement of said arm from one position to the other, the head is timed to oscillate from front to profile and profile to front, and means adapted to simulate the act of smoking through the mouth and nose of the head concurrently with said movements of the head and the arm.
